(57) **CLAIM**

We claim the ornamental design for an outdoor unit for air conditioner, as shown and described.

DESCRIPTION

FIG. 1 is a perspective view of an outdoor unit for air conditioner showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is an enlarged view of portion "8" shown in FIG. 1. The broken lines depict portions of the outdoor unit for air conditioner that form no part of the claimed design. The dot-dot-dash lines in FIGS. 1 and 8 define the boundary of the enlargement area and form no part of the claimed design.
